US00D657659S

(12) **United States Design Patent**
Bucci

(10) **Patent No.:** **US D657,659 S**
(45) **Date of Patent:** **** Apr. 17, 2012**

(54) **DEVICE FOR SUPPORTING AN OBJECT**

(76) Inventor: **Michael Bucci**, Glen Allen, VA (US)

(**) Term: **14 Years**

(21) Appl. No.: **29/396,375**

(22) Filed: **Jun. 29, 2011**

Related U.S. Application Data

(60) Continuation of application No. 29/381,968, filed on Dec. 27, 2010, now Pat. No. Des. 642,447, which is a continuation of application No. 29/355,157, filed on Feb. 3, 2010, now Pat. No. Des. 631,729, which is a continuation of application No. 29/352,511, filed on Dec. 22, 2009, now Pat. CLAIM

I claim the ornamental design for a device for supporting an object, as shown and described.

DESCRIPTION

FIG. 1 is a perspective view of a device for supporting an object showing the new design.

FIG. 2 is a front elevational view thereof.

FIG. 3 is a rear elevational view thereof.

FIG. 4 is a top view thereof; and,

FIG. 5 is a bottom view thereof.
